UNITED STATES PATENT OFFICE.

KARL BERGVELT, OF GRAND RAPIDS, MICHIGAN.

DESIGN FOR A PHONOGRAPH-CABINET.

56,853.

Specification for Design.

Patented Jan. 4, 1921.

Application filed September 15, 1919. Serial No. 324,028. Term of patent 7 years.

To all whom it may concern:

Be it known that I, KARL BERGVELT, a subject of the Queen of Holland, residing at Grand Rapids, in the county of Kent and State of Michigan, have invented a new, original, and ornamental Design for a Phonograph-Cabinet, of which the following is a specification, reference being had to the accompanying drawing, forming a part thereof.

In the drawing, the figure is a perspective view of the cabinet.

I claim:

The ornamental design for a phonograph cabinet, substantially as shown.

In testimony whereof, I hereunto affix my signature.

KARL BERGVELT.
